(57) **CLAIM**

The ornamental design for a double sided sign holder, as shown and described.

DESCRIPTION

FIG. 1 is a perspective view from the upper left of a double sided sign holder showing my new design;

FIG. 2 is a perspective view from the lower left thereof;

FIG. 3 is a right side elevational view thereof, with the left side elevational view being a image thereof;

FIG. 4 is a top plan view thereof;

FIG. 5 is a bottom plan view thereof; and,

FIG. 6 is a front view thereof, with a rear view being a mirror image thereof.
